UNITED STATES PATENT OFFICE.

WILLIAM E. SHAVER, OF WELDON, ILLINOIS.

COMBINED REEL AND BARREL-CARRIER.

SPECIFICATION forming part of Letters Patent No. 695,241, dated March 11, 1902.

Application filed April 22, 1901. Serial No. 56,900. (No model.)

To all whom it may concern:

Be it known that I, WILLIAM E. SHAVER, a citizen of the United States, residing at Weldon, in the county of Dewitt and State of Illinois, have invented new and useful Improvements in a Combined Reel and Barrel-Carrier, of which the following is a specification.

My invention relates to vehicles adapted for use as a wire-winding reel and also as a water-carrying cart.

The object of the invention is to provide a simple and effective construction of vehicle which may be readily converted into either a winding-reel or water-carrying apparatus.

The construction of the improvement will be fully described hereinafter in connection with the accompanying drawings, which form a part of this specification, and its novel features will be defined in the appended claims.

In the drawings, Figure 1 is a plan view of the invention constructed and equipped as a winding-reel for wire-fencing. Fig. 2 is a side elevation of the same. Fig. 3 is a rear elevation of the improvement constructed for use as a water-carrying apparatus. Fig. 4 is a view in perspective of a portion of the winding-reel and one of the clutch members thereof. Fig. 5 is a view in perspective of one of the castings employed upon the axle of the vehicle. Fig. 6 is a perspective view of a brake device adapted for use with the improvement.

Referring to Figs. 1 and 2, the reference-numeral 1 designates an axle, upon the ends of which are mounted carrying-wheels 2 and 3. To the upper surface of the axle 1, adjacent to each end thereof, is a casting comprising a longitudinally-disposed plate 4, recessed on its upper surface, a depending bearing 5, through which the axle extends, and a laterally-projecting arm 6, formed with openings to receive bolts 7, which secure the casting to the axle. The plates 4 of the castings are also formed with openings to receive bolts 8, which secure the rear ends of the bars 9 and 10 to the axle.

11 designates a revoluble shaft supported by bearings 12 and 13, secured to the upper surfaces of the bars 9 and 10. The bearing 13 comprises a fixed member, which is secured to the upper surface of the bar 10, and a

hinged member adapted to be secured in proper relation to the fixed member of the bearing by means of a removable pin 14. 55

15 designates a sprocket-pinion mounted upon one end of the shaft 11 in alinement with a sprocket-wheel 16, secured to the wheel 3, concentric therewith, and an endless sprocket-chain 17 connects the wheels 15 and 60 16 to revolve the shaft 11.

The shaft 11 is adapted to carry a reel upon which is to be wound the wire, the construction of which, as illustrated in the accompanying drawings, is a common form of reel 65 comprising parallel spiders 18 and 19, mounted upon the shaft 11 and connected by horizontal connecting-rods 20, around which the wire is to be wound, as illustrated in Fig. 1.

Upon the shaft 11, adjacent to the bar 10, 70 is arranged a clutch device comprising a stationary member 21, which is fixed to the shaft, and a movable member 22. The meeting faces of the two clutch members are formed with oppositely-arranged ratchet-teeth and are normally held in engagement with each other by means of the spring 31. 75

Projecting in opposite directions from the movable clutch members 22 are arms 23 and 24, having at their outer ends projections 25, 80 which are adapted to engage the opposite edges of one of the members forming the spider 18.

The operation of the machine as thus far described is as follows: In reeling wire the 85 operator pushes the machine in front of him, the reel revolving in the direction of revolution of the wheels 2 and 3, the wire passing under the axle and winding upon the reel from the under side thereof. In case there 90 is too much strain the spring 31 yields, and the inclined teeth of the clutch member 22 slide upon the teeth of the fixed member 21, thus relieving the strain automatically. In unreeling the machine is pulled instead of 95 pushed, the wire passing from the top of the reel and over instead of under the axle. The clutch members 21 and 22 are separated during unreeling and are held apart by the brake device shown in Fig. 6, comprising a plate 32, 100 having a longitudinal slot to adapt the plate to fit over the shaft 11 and a pair of perforated lugs 33, adapted to be secured to the member 22 by any suitable means. Thus the

clutch members are permitted to revolve in opposite directions.

Referring to Fig. 3, 26 designates a barrel, to which are secured at diametrically opposite points, near the upper end thereof, trunnions 27, formed integral with plates 28, which latter are provided with openings to receive bolts or rivets which secure the trunnions to the barrel. When the device is to be used as a water-carrying apparatus, the shaft 11 and the reel and clutch mechanism shown in Figs. 1 and 2 are removed, and the trunnions 27 are supported in the bearings 12 and 13, as illustrated in Fig. 3.

To the inner side of each of the thills 9 and 10 is pivotally secured the upper end of a folding brace or leg 29. These legs are provided with means for supporting them in their elevated position, the means shown in the drawings being hooks 30.

I claim—

1. A combined reel and barrel-carrier, comprising parallel bars, a folding leg to each bar, a plate at one end of each bar, said plates

being recessed for the reception of the ends, 2 a depending bearing to each plate, an axle projecting therethrough, a laterally-projecting arm on each plate and secured to the axle, and bearings on the bars adapted to receive a reel-shaft or barrel-trunnion. 3

2. In a combined reel and barrel-carrier, the combination with an axle and parallel bars, of a shaft supported in bearings on the bars, means for revolving the shaft, a reel mounted on the shaft, a clutch device comprising a 3 member fixed on the shaft, a spring-pressed movable member, and arms projecting from the movable member and having projections engaging the reel, and a brake device comprising a slotted plate adapted to be interposed between the clutch members. 4

In testimony whereof I affix my signature in presence of two witnesses.

WILLIAM E. SHAVER.
